FOOT CONTROL SWITCH

Peter H. Voorlas, Racine, Wis.

Application June 13, 1955, Serial No. 36,492

Term of patent 14 years

(Cl. D26—13)

FIG. 1

FIG. 2

Fig. 1 is a top plan view of a foot control switch showing my new design; and

Fig. 2 is a front elevational view thereof.

I claim:

The ornamental design for a foot control switch, substantially as shown.
